UNITED STATES PATENT OFFICE.

JOSEPH KROGMAN, OF PLAIN, WISCONSIN.

REPAIR STAND.

Application filed June 1, 1928. Serial No. 282,126.

The present invention relates to improvements in repair stands for use in automobile repair shops, and has reference more particularly to a device for use in facilitating the removal of the springs of overhead valves whereby to permit the valves to be removed for cleaning purposes, and to further facilitate grinding of the valves.

One of the important objects of the present invention is to provide a repair stand which includes a pivoted cradle upon which is adapted to be secured the head of the motor carrying the valves and the springs associated therewith, means being provided for positively securing the head in a rigid manner on the cradle, the cradle being mounted for swinging movement in a frame, means being provided for locking the cradle against swinging movement.

20 A further object is to provide a repair stand of the above mentioned character wherein means is provided for preventing the displacement of the valves after the springs have been removed from the upper ends of the valve stems, said means being removable when the cradle is reversed, in order to permit the removal of the valves or to facilitate grinding of the same while remaining in said engine head that is secured on the cradle.

25 Still a further object is to provide a repair stand of the above mentioned character wherein the same includes a valve spring depressing member that is removably supported in a yoke, and which yoke is mounted for rotation on the upper end of a rod, whereby said valve spring depressor may be positioned over any one of the valve stems, means being provided for normally holding the valve spring depressor member in a raised inoperative position, a foot operated member being provided to effect the downward movement of the valve spring depressor after the same has been properly positioned over one of the valve stems, whereby to compress the spring and facilitate the removal of the key and said spring.

30 A further object is to provide a repair stand of the above mentioned character which is simple in construction, inexpensive, strong and durable and further well adapted to the purpose for which it is designed.

35 Other objects and advantages of the invention will become apparent from the following description when taken in connection with the accompanying drawings.

In the accompanying drawings wherein like reference characters indicate corresponding parts throughout the several views:

Figure 1 is a top plan view of the repair stand embodying my invention showing the head of a motor provided with overhead valves secured in its proper position on the cradle.

Figure 2 is a vertical sectional view through the cradle showing the head of the motor secured thereon, and showing the valve spring depressing mechanism in side elevation.

Figure 3 is a top plan view of the repair stand with the head of the engine removed and showing the valve supporting bar secured longitudinally on the cradle.

Figure 4 is a detail perspective view of the pan forming a part of the invention.

Figure 5 is a cross sectional view through the pan showing the manner in which the same is supported on the frame.

Figure 6 is a side elevation of the repair stand, parts being shown in section.

Figure 7 is a detail sectional view showing the securing means for one end of the valve supporting bar.

Figure 8 is an end elevation of the repair stand, parts being shown in section, and

Figure 9 is a detail perspective view of the horizontally disposed rod that supports the valve spring depressor element in its outer end.

In the drawings wherein for the purpose of illustration is shown the preferred embodiment of my invention, the numeral 1 designates a substantially circular base and extending upwardly from the central portion thereof is the tubular standard 2, the lower end portion of which is formed with the longitudinal slot 3, as shown more clearly in Figure 8, and the purpose thereof will be presently described.

40 A substantially U-shaped frame 4 has its base portion secured on the upper end of the standard 2 at its intermediate portion in such a manner as to provide a unitary structure.

45 Forming a salient part of the present invention is the cradle, designated generally by the numeral 5, and this cradle comprises a substantially rectangular shaped frame, the longitudinal sides of which are disposed in a plane at right angles to the ends of the frame. Furthermore the vertically disposed end portions 6 of the rectangular shaped cradle 5 gradually converge in a downward direction.

toward their intermediate portions as more clearly disclosed in Figure 2.

The cradle 5 is disposed horizontally between the upper ends of the arms of the U-shaped stationary frame 4 and suitable pivot forming bolts 7 extend through the intermediate portions of the respective ends of the cradle and the upper ends of the adjacent arms of the U-shaped frame 4 whereby said cradle is pivotally mounted in the top of the stationary frame.

A laterally extending handle 8 is arranged at one end of the cradle 5 and forms a continuation of one of the ends 6 as shown very clearly in Figures 1 and 3 of the drawing, and a knob 9 is carried on the outer end of this handle. This provides a means whereby the cradle may be manually swung on its pivots 7, as will be hereinafter described in detail.

For the purpose of holding the cradle 5 in a horizontal position against swinging movement, there is provided the elongated lever 10 that is pivoted at its upper end to the other end of the cradle 5 as at 11, and this lever extends downwardly through a slot 12 formed in the base portion of the U-shaped frame 4 adjacent the vertically disposed arm 13 of said frame, and an actuating handle 14 is arranged on the lower end of the lever. As is more clearly disclosed in Figure 6, the pivoted lever is formed with an offset nose 15 that is held in engagement with the base of the U-shaped frame 4 by means of the spring 16 and when the handle 14 is actuated in a particular manner, the nose 15 is disengaged from the base of the frame to facilitate the swinging of the cradle by actuating the handle 8 and the knob 9 arranged on the outer end thereof for completely turning over the cradle.

Extending upwardly from the longitudinal sides of the cradle 5 adjacent the respective corners thereof are the stud bolts 17 and the same are adapted to project through the apertured adjacent lugs 18 that extend from the sides of the head 19 of a motor, the head in the present instance being that of a motor of the Chevrolet type. Suitable nuts 20 are threaded on the upper ends of the stud bolts for engagement with the top faces of the respective lugs 18 for rigidly securing the head 19 on the cradle, as shown clearly in the drawings and for the purpose of supporting the valves from dropping out of the head 19 after the springs have been removed from the upper ends of the valve stems. I provide the longitudinally extending valve supporting bar 21 that extends longitudinally beneath the central portion of the head 19 and the ends of this bar 21 are slotted as shown at 22 with reference more particularly to Figure 7. An angular bracket 23 is carried by the intermediate portion of each end 6 of the cradle 5, and the slotted ends of this bar 21 rest on the hori-

zontal portions of the respective brackets, and a bolt 24 projects through the horizontal portion of each bracket for disposition through the adjacent slotted end of the bar 21, and a thumb nut 25 is threaded on the upper threaded end of the bolt, in the manner as also shown in Figure 7 to positively secure the valve supporting bar in a rigid position on the cradle frame.

Also forming an important part of the present invention is the rod 26 that is disposed in the tubular standard 2 for vertical sliding movement, the upper portion of this rod extending through the base of the U-shaped frame, and thence being disposed laterally as at 27 and thence upwardly as at 28 for disposition at the rear side of the cradle, and the upper end of this rod projects above the head 19, and has removably supported thereon the yoke 29.

A horizontally disposed arm 30 is slidably arranged through registering openings formed in the upper ends of the arms of the yoke 29 and one end of this arm is formed with a vertically disposed eye or collar 31, as clearly shown in Figure 9.

The intermediate portion of the arm 30 rests on the upper end of the rod 28 to prevent downward sliding movement of the yoke 29 with respect to this portion of the rod and supported in the vertically disposed eye or collar 31 is the shank 32 that has arranged on its lower end a valve spring depressor 33, a knob 34 being detachably secured on the upper end of the shank.

The yoke 29 is capable of rotary movement on the upwardly disposed portion 28, and normally this part of the device is disposed in the position shown in Figure 3.

The actuating means for this mechanism comprises a foot lever 35 that has its intermediate portion projecting through the slotted lower end 3 of the tubular standard 2 as well as through a slot formed in the lower end of the rod 26 and the rear end of this foot lever is pivoted in an upstanding bracket 36 arranged on the base 1, while a foot treadle 37 is arranged on the forward end of this foot lever. A retractile coil spring 38 is connected at its lower end to the pivoted end portion of the foot lever 35, while the upper end is secured to the standard 2 for the purpose of normally holding the foot lever 35 in a raised position whereby to hold the rod 26 and the parts carried on the upper end thereof in a raised inoperative position.

A pan 39 has its intermediate portion formed with the recess 40 to accommodate the rod 26 and this pan rests in a horizontal manner on the base portion of the frame 4 and is detachably secured thereon by means of the spring clips shown at 41 in Figure 5, the spring clips engaging with the base portion of the U-shaped frame 4. This pan is provided for catching any oil that may drop

from the head of the motor, while the necessary repairs are being made to the valves.

When the motor head 19 is secured on the cradle 5 in the manner as shown in Figure 1, the operator may grasp the knob 34 and slide the arm 30 outwardly or more particularly forwardly so that the valve spring depressor 33 will be disposed over any one of the valve stems 42, and when properly positioned thereover, the steps on the treadle 37 thereby moving the foot lever 35 downwardly which will result in the rod 36 moving downwardly and at the same time causing the member 33 to engage with the spring 43 of the selected valve stem so that the particular spring will be depressed to permit the removal of the key 44, and said spring. This operation is repeated until all the keys and springs have been removed from their respective valve stems. It is of course understood that as soon as pressure is taken off of the foot lever, the retractile coil spring 38 will automatically move the parts to their initial inoperative position, as shown in Figure 2.

The bar 21 will prevent the valves from dropping downwardly out of the head 19. As before mentioned, all of the springs and keys are removed from the upper ends of the valve stems after which the cradle is swung a complete revolution on its pivots 7 by disengaging the locking lever 10 from the frame 4, and actuating the handle 8 so that the head 19 will be disposed in an upside down position, after which the frame is again locked against swinging movement. This will permit the valve to be readily removed from the head or to facilitate grinding of the valves, while positioned in the head, with the use of any conventional valve grinding tool.

When the head 19 is turned upside down, the arm 30 will be disposed parallel with the rectangular shaped cradle 5 in an out of the way position as shown very clearly in full lines in Figures 1 and 3 of the drawings.

It will thus be seen from the foregoing description, that I have provided a repair stand that is particularly adapted to be used in working upon the valves of a head of a motor that employs overhead valves, and by reason of its simplicity the parts can be readily and easily adjusted and actuated.

Furthermore a repair stand of this character will be strong and durable and at all times positive and efficient in carrying out the purpose and easily adjusted and actuated.

While I have shown the preferred embodiment of my invention it is to be understood that minor changes in the size, shape and arrangement of parts may be resorted to without departing from the spirit of the invention and the scope of the appended claims.

Having thus described the invention, what I claim as new and desire to secure by Letters Patent is:—

1. In a repair stand of the class described,

a frame, a horizontally disposed engine head supporting cradle mounted in the frame for swinging movement, means for securing said cradle in a stationary position, means for securing a motor head on the cradle, a member carried by the cradle for disposition beneath said head to prevent the dropping out of the valves from the head during the removal of the springs and the key from the valve stems of said valves, means for facilitating the compression of the valve springs while the head is mounted on the cradle, the last mentioned means including a horizontally disposed arm, a vertically movable support therefor, a valve spring compressing element carried by the outer end of said arm, said arm being capable of sliding and swinging movement in a horizontal plane for positioning the valve spring compressing member over any one of the valve springs, means for normally holding the support for the arm in a raised position to maintain the valve spring compressing member in an inoperative position, and means for actuating said vertically movable support to move the valve spring compressing member into engagement with the selected valve spring.

2. In a repair stand of the class described, a base, a tubular standard extending upwardly therefrom, a substantially U-shaped stationary frame mounted on the upper end of the standard, a motor head supporting cradle mounted between the upper ends of the arms of said U-shaped frame for swinging movement, means for securing the head on the cradle, means for locking the cradle in a stationary position, a bar detachably secured on the cradle and extending longitudinally beneath the head of the motor to support the valves of the head from dropping out when the head is positioned on the cradle, and means for compressing the valve springs associated with the upper ends of the valves that project through the top of the head to facilitate removal of the springs and the locking keys, said cradle being swung to a reverse position when the locking means therefor is released to permit removal of the valve holding bar, and said valves.

3. In a repair stand of the class described, a base, a tubular standard extending upwardly therefrom, a substantially U-shaped stationary frame mounted on the upper end of the standard, a motor head supporting cradle mounted between the upper ends of the arms of said U-shaped frame for swinging movement, means for securing the head on the cradle, means for locking the cradle in a stationary position, a bar detachably secured on the cradle and extending longitudinally beneath the head of the motor to support the valves of the head from dropping out when the head is positioned on the cradle, and means for compressing the valve springs associated with the upper ends of

the valves that project through the top of the head to facilitate removal of the springs and the locking keys, said cradle being swung to a reverse position when the locking means therefor is released to permit removal of the valve holding bar, and said valves, the last mentioned means comprising a rod slideable in the tubular standard and through the base of the U-shaped frame, 10 the intermediate portion of said rod being disposed laterally, the upper end of the rod being disposed upwardly, a yoke mounted on the upper end of the rod for rotation thereon, an arm disposed horizontally through the 15 upper ends of the arms of the yoke for rest upon the upper end of said rod, a valve spring depressing member carried by the outer end of said arm and adapted to be selectively positioned over any one of the valve 20 springs, said valve depressing member being normally held in a raised inoperative position, and means operable near the base for moving the valve depressing member into a lowered operative position for engagement with the selected valve spring. 25

4. In a repair stand of the class described, a base, a tubular standard extending upwardly therefrom, a substantially U-shaped stationary frame mounted on the upper end 30 of the standard, a motor head supporting cradle mounted between the upper ends of the arms of said U-shaped frame for swinging movement, means for securing the head on the cradle, means for locking the cradle 35 in a stationary position, a bar detachably secured on the cradle and extending longitudinally beneath the head of the motor to support the valves of the head from dropping out when the head is positioned on the cradle, 40 and means for compressing the valve springs

associated with the upper ends of the valves that project through the top of the head to facilitate removal of the springs and the locking keys, said cradle being swung to a reverse position when the locking means therefor is released to permit removal of the valve holding bar, and said valves, the last mentioned means comprising a rod slideable in the tubular standard and through the base of the U-shaped frame, the intermediate portion of 45 said rod being disposed laterally, the upper end of the rod being disposed upwardly, a yoke mounted on the upper end of the rod for rotation thereon, an arm disposed horizontally through the upper ends of the 50 arms of the yoke for rest upon the upper end of said rod, a valve spring depressing member carried by the outer end of said arm and adapted to be selectively positioned over any one of the valve springs, said 55 valve depressing member being normally held in a raised inoperative position, means operable near the base for moving the valve depressing member into a lowered operative position for engagement with the selected 60 valve spring, said last mentioned means comprising a foot lever having its intermediate portion extending through the tubular standard, said standard being mounted to accommodate the lever, the lower end of the rod being formed with a slot through which the 65 foot lever extends, one end of the lever being pivoted on the base, a foot treadle on the free end of the lever, and a retractile coil spring 70 connecting the pivoted end of the foot lever 75 with the standard to normally hold the foot lever and said rod in a raised position.

In testimony whereof I affix my signature.

JOSEPH KROGMAN.
